ALLEN C. FEARING, OF SOUTH WEYMOUTH, MASSACHUSETTS, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

FASTENER-PART-FEEDING MECHANISM FOR FASTENER-ATTACHING MACHINES

Application filed June 22, 1927; Serial No. 200,603. Renewed May 27, 1930.

My invention aims to provide improvements in fastener-part feeding mechanisms for fastener-attaching machines.

In the drawings, which illustrate a preferred embodiment of my invention:

Figure 1 is a plan view of the fastener-feeding means, the ends of fastener-part conveying chutes, and portions of fastener-part-attaching means being shown in association therewith;

Fig. 2 is a plan section of one of the fastener-feeding mechanisms showing the relation of the fastener parts and the movable parts of the feeding mechanism in position for depositing a fastener-part upon the receiving part of the fastener-attaching means;

Fig. 3 is a view similar to Fig. 2 but showing the parts of the feeding mechanism at the beginning of the feeding stroke to move the fastener parts toward the fastener-attaching means;

Fig. 4 is a section on the line 4—4 of Figure 1, showing portions of the fastener-feeding mechanisms; and

Fig. 5 is a section on the line 5—5 of Figure 1, showing the fastener-attaching means in the operation of securing fastener parts to a suitable carrying medium.

Referring to the drawings, I have illustrated mechanisms for selecting and feeding snap fastener parts in connection with a machine for attaching the fastener parts to a suitable fastener-carrying medium. Any suitable type of fastener-attaching machine may be used, and, therefore, I have shown in the drawings only enough of the other parts of the machine to permit a clear description of the operation of the fastener-selecting and feeding mechanism. For the purpose of illustration merely, I have shown fastener-feeding mechanisms in connection with a fastener-attaching machine for securing stud members 1 to a carrying medium 2 by means of rivets 3, the attaching means being clearly shown in Fig. 5. It should be understood that the same mechanisms may be employed in other like machines.

The fastener-attaching means, illustrated in Fig. 5, includes a spreadable stud-receiving

holder 4 having a depression 5 in which the stud may rest. Above the spreadable holder 4, I have provided a reciprocable plunger or die member 6 adapted to be forced downwardly by any suitable means (not shown). This plunger 6, during its downward movement, picks the stud member 1 from the depression 5 in the spreadable holder 4 and forces it downwardly toward the carrying medium 2 resting upon a spring-pressed plate 7 supported upon a table 8. Directly below the die member 6, I have shown a fixed die member 9 secured to the table 8 for receiving the tubular rivet 3.

In this application, my invention is directed primarily to the means for selecting and transferring the rivet portions from the end of the chute 10 to the die member 9 and also to the means for selecting and delivering the stud members 1 from the chute 11 to the spreadable holder 4. The mechanism which I have shown for transferring the rivets 3 is substantially the same and includes the same elements as the mechanism shown for transferring the stud members 1. The only differences in the two mechanisms are in their location with relation to each other and with relation of the chutes. These differences necessitate forming the pathways A and B along which the fastener elements 1 and 3 are moved just the reverse with relation to each other. In Figure 1, I have shown, in plan, the general relation of the fastener-feeding mechanisms with the attaching means and with the chutes which deliver the fastener parts to the fastener-feeding mechanisms. The rivets 3 may be fed down the chute 10 from any suitable source of supply (not shown), and are selected by the reciprocating part 12 and directed thereby along the straight portion 13 of the pathway A, shown in dotted lines. They are transferred from the straight portion 13 to the straight portion 14 through the connecting portion 15 by means of a spring-pressed finger 16, all of which will be more fully herein-after described. The stud members 1

may be fed down the chute 11 from any suitable source of supply (not shown). They are selected by the reciprocating part 17 and moved along the straight portion 18 of the pathway B from which they are transferred to the straight portion 19 of the pathway B through the connecting portion 20 by means of the spring-pressed finger 21. The purposes of the spring-pressed finger 21 will be more fully hereinafter described. As the operation of the mechanism which feeds the rivet parts 3 from the chute 10 to the die member 9 is substantially the same as the operation of the mechanism for feeding the stud members from the chute 11 to the spreadable part 4, it will suffice to describe one of the mechanisms. Therefore, I have elected to describe the mechanism for feeding the stud members 1 as shown in Figs. 2 and 3. The stud-feeding mechanism includes a base plate 22 into which is cut the pathway B along which the stud members are moved. The spring-pressed finger 21 is supported in a groove 23 cut into the base plate, as shown in Figs. 2 and 3, and the end of the chute 11 is also secured to the base plate adjacent to the pathway as illustrated. The reciprocating part 17 may be mounted upon the plate 22 for reciprocation above the pathway B in any suitable manner. However, I have shown, in Figure 1, a pair of guide members 24 and 25 secured to the plate 22 and holding and guiding the reciprocating member 17. In Figure 1, I have also shown a cam 26 mounted on a shaft 27 adapted to be rotated by suitable means (not shown). The cam bears against a roller 28 located at one end of the reciprocating part 17. This roller is held in contact with the cam by means of the spring 29 acting to pull the reciprocating part 17 toward the cam. The feeding end of the reciprocating part 17 is cut away beneath the upper surface, as shown in Figs. 2 and 3, to provide the shoulders 30 and 31 for contact with the stud members 1 to move them forward. I have also shown, in Figs. 1 through 3, the reciprocating part 17 as having a curved end portion which provides a cam surface 32 along one edge against which the pin 33 carried by the spring-pressed finger 21 may bear. Thus, when the reciprocating part 17 is moved forward, the cam surface 32, (shown in dotted lines, Figs. 2 and 3,) will act upon the pin 33 to return the spring-pressed finger 21 to a position beyond the edge of the straight portion 18 of the pathway B, as shown in Fig. 2.

The selecting and feeding operation of the stud-feeding mechanism is as follows:—Assuming that the reciprocating part 17 has made one complete reciprocation, a stud member 1 will be positioned in the straight portion 19 of the pathway B, having been

moved into this position from the straight portion 18 by the spring-pressed finger 21, as shown in Fig. 3, and a second stud member will be positioned in the straight portion 18 of the pathway B as indicated in Fig. 3. As the reciprocating part 17 is moved toward the fastener-attaching means by the cam 26, the shoulder 30 will engage the stud 1 in the straight portion 19 of the pathway B and the shoulder 31 will engage the stud 1 in the straight portion 19 of the pathway B and both studs will be moved forwardly to the positions shown in Fig. 2. The stud member in the straight portion 19 of the pathway B is moved upon the spreadable part 4 during this forward movement of the part 17. Also, during this movement of the part 17, the cam surface 32 of the reciprocating part 17 engages the pin 33 and moves the spring-pressed finger 21 to the position shown in Fig. 2, so that the stud member 1 in the straight portion 18 of the pathway B may be positioned opposite the end of the finger 21. The straight edge 34 of the reciprocating part 17 contacts with the stud member located at the end of the chute 11 and prevents it from entering the pathway B during the entire stroke of the reciprocating part 17. The fastener-setting means is operated to dispose of the stud member 1 located upon the part 4, and the spring-pressed finger 21 moves the stud part 1 through the connecting portion 20 of the pathway B to the straight portion 19 and another stud member may enter the pathway B from the end of the chute 11, as shown in Fig. 3. By this arrangement and operation of parts, I shorten the length of the stroke of the reciprocating part 17 by one-half the distance between the end of the chute 11 and the recess 5 in the part 4. After the feeding mechanism is once operated, a stud member 1 is delivered to the part 4 at each reciprocation of the part 17, so long as there are fastener parts in the chute. It should be understood that the length of the stroke may be reduced even more than I have shown and described by providing more shoulders corresponding with the shoulders 30 and 31 and more offset straight portions corresponding with the offset straight portions 18 and 19 of the pathway B. For instance, instead of requiring two reciprocations to feed the stud member from the end of the chute 11 to the part 4, I may require three or four or more reciprocations, according to the arrangement of the pathway and the various shoulders formed upon the reciprocating part 17. It should, of course, be understood that the length of the cam 26 will be reduced to correspond with the desired length of travel of the reciprocating part 17.

A second cam 26^a (Fig. 1) mounted upon the shaft 27 contacts with the roller 28^a secured to the end of the reciprocating part 12

so that the means for feeding the rivet parts 3 of the fastener may be operated at the same time and in conjunction with means for feeding the stud elements. Therefore, whenever a stud member is placed upon the part 4, a rivet part will also be placed upon the die member 9, in substantially the same manner as above described in connection with the stud-feeding mechanism.

For the purpose of reference merely, I have supplied the parts of the rivet-feeding mechanism with numerals corresponding to the numerals of like parts of the stud-feeding mechanism. These numerals are distinguished by adding the letter "a", except in instances where the parts have been specifically referred to in the above description.

While I have shown and described a preferred embodiment of my invention, I do not wish to be limited thereto, my invention being best described in the following claims.

Claims:

1. In a fastener-attaching machine having a setting die and a chute for guiding fastener parts, the end of the chute being remote from the setting die, a mechanism for feeding the fastener parts from the chute to the die, said mechanism comprising means providing a pathway leading from the end of the chute to the die and provided with connected laterally offset portions disposed in a horizontal plane, a fastener-feeding element for moving a fastener part along each offset portion of the pathway at each operation of the feeding element thereby providing for step by step feeding of the fastener part from the end of the chute to the setting die, and means operable transversely of the offset portions of the pathway to move a fastener element from one offset portion to another by way of the connecting portion of the pathway.

2. In a fastener-attaching machine, having a setting die and a chute for guiding fastener parts, the end of the chute being remote from the setting die, a mechanism for feeding the fastener parts from the chute to the die, said mechanism comprising means providing a pathway leading from the end of the chute to the die and provided with connected laterally offset portions disposed in a horizontal plane and leading toward the setting die, to provide an irregular, as distinguished from a straight line, pathway, a reciprocable feeding element provided with means for moving a fastener part along each offset portion of the pathway during its movement toward the die, and a spring-pressed finger operable transversely of the offset portions of the pathway for moving a fastener part from one offset portion of the pathway to another during the return movement of the reciprocable element.

3. In a fastener-attaching machine, hav-

ing a setting die and a chute for guiding fastener parts, the end of the chute being remote from the setting die, a mechanism for feeding the fastener parts from the chute to the die, said mechanism comprising means providing a pathway leading from the end of the chute to the die, the pathway having connected offset portions leading toward the setting die, a reciprocable feeding element provided with means for moving a fastener part along each offset portion of the pathway during its movement toward the die, a reciprocable finger for moving a fastener part from one offset portion of the pathway to another during the return movement of the reciprocable element, and cam means cooperating between the finger and the feeding element for moving said finger in one direction during the feeding stroke of the feeding element.

4. In a fastener-attaching machine, a mechanism for selecting and feeding fastener parts to a setting die, said mechanism comprising means providing a pathway for guiding the fastener parts to the setting die, the pathway being provided with connected offset portions, feeding means for moving the fastener parts along the offset portions of the pathway, resiliently operable means for moving the fastener parts from one offset portion of the pathway to another portion, and cam means for returning the resiliently operable means to its normal position.

5. In a fastener-attaching machine, a mechanism for selecting and feeding fastener parts to a setting die, said mechanism comprising means providing a pathway for guiding the fastener parts to the setting die, the pathway being provided with connected offset portions, feeding means for moving the fastener parts along the offset portions of the pathway, resiliently operable means for moving the fastener parts from one offset portion of the pathway to another portion, and cam means forming part of the feeding means for returning the resiliently operable means to its normal position.

6. In a fastener-attaching machine, a mechanism for selecting and feeding fastener members to a setting die, said mechanism comprising a stationary part having a pathway for the fastener members, said pathway being in the form of connected laterally offset portions disposed in a horizontal plane and along which the fastener members are moved in a step by step manner, a part reciprocable longitudinally relative to the offset portions of said pathway and provided with means for moving a fastener member along one of the offset portions of the pathway at each reciprocation thereof thereby providing a step by step feeding of the fastener members along the offset por-

tions of the pathway to a setting die, and means located adjacent to the connecting portion of the pathway whereby the fastener member is moved from one offset portion of the pathway to another.

7. In a fastener-attaching machine, a mechanism for selecting and feeding fastener members to a setting die, said mechanism comprising a stationary part having a pathway for the fastener members, said pathway being in the form of connected laterally offset portions disposed in a horizontal plane and along which the fastener members are moved in a step by step manner, a part reciprocable longitudinally relative to the offset portions of said pathway and provided with means for moving a fastener member along one of the offset portions of the pathway at each reciprocation thereof thereby providing a step by step feeding of the fastener members along the offset portions of the pathway to a setting die, and reciprocable means operable transversely relative to the offset portions of the pathway and located adjacent to the connecting portion to move a fastener member from one offset portion of the pathway to another.
8. In a fastener-attaching machine, a mechanism for selecting and feeding fastener members to a setting die, said mechanism comprising a stationary part having a pathway for the fastener members, said pathway being in the form of connected laterally offset portions disposed in a horizontal plane and along which the fastener members are moved in a step by step manner, a part reciprocable longitudinally relative to the offset portions of said pathway and provided with fastener engaging means each of which is in alignment with a corresponding part of the pathway for moving a fastener member along each of the offset portions of the pathway at each reciprocation thereof thereby providing a step by step feeding of the fastener members along the offset portions of the pathway to a setting die, and means located adjacent to the connecting portion of the pathway whereby the fastener member is moved from one offset portion of the pathway to another.

In testimony whereof I have signed my name to this specification.

ALLEN C. FEARING.
